UNITED STATES PATENT OFFICE.

GLENN J. BARRETT, OF SYRACUSE, NEW YORK, ASSIGNOR TO BURROUGHS ADDING MACHINE COMPANY, OF DETROIT, MICHIGAN, A CORPORATION OF MICHIGAN.

AUTOMATIC INK-RIBBON-REVERSING MECHANISM.

1,065,769.

Specification of Letters Patent.

Patented June 24, 1913.

Application filed December 4, 1906. Serial No. 346,280.

To all whom it may concern:

Be it known that I, GLENN J. BARRETT, a citizen of the United States, residing at Syracuse, Onondaga county, New York, have invented certain new and useful Improvements in Automatic Ink-Ribbon-Reversing Mechanism, of which the following is a specification.

The principal object of the present invention is to relieve the ribbon of any work in the actual shifting or reversing of the driving mechanism, its duty in this connection being merely to set certain devices which will then be actuated from the same source of power which is drawn upon to feed the ribbon.

Another object of the invention is to provide a simple and durable ribbon reversing construction not likely to become disordered from constant use.

With these objects in view, the invention consists in certain novel features of constructions and combinations of parts the essential elements of which are recited in the appended claims and a preferred form of embodiment of which is described in detail hereinafter and fully illustrated in the accompanying drawings forming part of this specification.

Of said drawings, Figure 1 represents in side elevation part of a recording machine in which the invention is embodied; Fig. 2 represents in rear elevation the ribbon mechanism with part of the driving connections; Fig. 3 represents a top plan view of the same; Fig. 4 represents in rear elevation some of the parts seen in Fig. 3, as they would appear in the act of reversing the ribbon feed; Figs. 5, 6 and 7 are diagrammatic views illustrating different relative positions of parts under different conditions.

For the purposes of illustration, the invention is shown embodied in a machine for recording items as is done in the well known adding machine. However, it is of course to be understood that the ribbon reversing mechanism of the present invention is not confined to use in this type of machine, but may be employed in any machine where an ink ribbon is used for taking impressions from type.

The reference numerals 2 and 3 designate the spools upon which the ribbon 4 is carried and the numeral 5 designates suitable guides over which the ribbon passes so as

to properly interpose it between the type 6 and the platen 7. These spools are mounted on spindles 8 and 9 suitably journaled in brackets 10 of an upright frame 11. Each spool carries a bevel gear 12, and a horizontal shaft 13, extending across the frame 11 and mounted to both rotate and slide therein, carries similar bevel gears 14 and 15. By moving said shaft lengthwise one or the other of said bevel gears thereon may be caused to mesh with one or the other of the spool gears. It will be seen that by turning this shaft with the gears in mesh one of the spools will be rotated and that the direction of rotation of this spool will be the reverse of that of the other spool when the shaft is shifted into gear with that other spool. The shaft carries a ratchet wheel 16 which is engaged by a long pawl 17 coupled to one end of a bell crank lever 18 the other end of which is connected to a link 19, coupled in turn to a rocking plate 20 of the adding machine. A link 21 connects another branch of this rocking plate with a short arm 22 secured to a rock shaft 23. Another arm 24 secured to this same rock shaft carries a roller 25 occupying a cam slot 26 in a plate 27 secured to a second rock shaft 28. This last named rock shaft has a crank arm 29 connected by a link 30 with a crank arm 31 on a third rock shaft 32, which carries an operating handle 33. It is not of course essential that the pawl 17 shall be actuated through such an extended series of operating connections. They simply happen to be those utilized in an embodiment of the present invention in a certain type of recording machine. Reciprocations of the operating handle 33, which cause operations of various parts of such a machine also operate to produce the desired reciprocations of the pawl 17, thus turning the shaft 13 and step by step and producing the requisite feed of the inking ribbon.

The brackets 10 support certain shifting devices, each of which comprises a horizontal spindle 36, an arm 37 at the forward end thereof having a rearwardly projecting pin 38, and a weighted arm 39 at the rear end of said spindle. The projecting pins 38 of these shifting devices extend behind the ribbon and the latter carries near its ends hooks 40 adapted to engage said pins. The arms 37 of the shifting devices have de-

2

pending extensions 41, which confront shoulders 42 respectively on the shaft 13, these shoulders being preferably formed by the hubs of the bevel gears 14 and 15. The 5 depending weighted arms 39 lie normally against the sides of the frame 11, holding the said extensions 41 away from the said shoulders 42 as shown in dotted lines in Fig. 3. Said weighted arms are preferably 10 formed with feet 43 to abut the sides of the frame 11 and they are also formed at their lower ends with rearwardly projecting lugs 44 beveled on their inner sides as shown more clearly in Figs. 5-7. The fingers 15 also normally lie against the sides of the frame 11, as shown in Fig. 3.

The rocking plate 20 is secured to a cross shaft 45 journaled in the frame 11 and this shaft carries a pair of arms 46 and 47, the 20 former of which may be and is here shown as integral with said rocking plate. These arms are oppositely bent at their upper ends to form outwardly projecting flanges 48 as shown in Fig. 3 and these flanges 25 have beveled forward edges as shown at 49 for coöperation with the beveled lugs 44. Normally, the arms 46 and 47 lie on the outer sides of said lugs as shown in Figs. 2 and 5 and the vibrations of said arms, 30 due to the rocking of the plate 20 in the operations of the machine, have no effect upon the shifting devices of which said lugs form a part.

In operation when the ribbon is about unwound from one of the spools, say for example the left hand spool in Fig. 3, the hook 40 at this end of the ribbon engages the lug 38 of the shifting device and rocks the latter sufficiently to throw the arm 41 35 against the shoulder 42 at the end of the shaft where the gears are out of mesh. This movement of the shifting device carries the lug 44 into the path of the beveled edge 49 of the flange 48 on the arm 46, see 40 Fig. 6. The ensuing vibration of said arm 46 will therefore cause the shifting device to be swung farther to the left (as the parts are viewed in Fig. 3) by reason of said beveled edge 49, acting against the beveled 45 edge of the lug 44 (see Fig. 4). This further movement of the shifting device causes the arm 41 to shift the shaft 13 to the left and engage the bevel gear 14 with the similar gear of the left hand ribbon spool, 50 and at the same time disengage the bevel gear 15 from the similar gear of the right hand ribbon spool. Consequently, in the continued step by step rotation of the shaft 13 the direction of movement of the ribbon 55 will be reversed, the same being wound upon the spool 2 and unwound from the spool 3. When the flange 48 has passed by the lug 44, the shifting device having done its work 60 may resume its normal position in the manner illustrated in Fig. 6.

It will be seen that the above described construction is well adapted to accomplish the objects primarily stated. No strain is brought upon the ribbon to perform any of the actual work of reversing the feed. The 70 ribbon simply sets a shifting device in position to be acted upon by operating connections from the source of power. Thus any objection to utilizing the draft of the ribbon for feed reversing purposes is obviated. 75 The simplicity of the construction and the unlikelihood of its becoming disordered through constant use will be apparent. While this particular construction thus fully attains the objects in view, it is to be 80 understood that the invention is not limited to the details thereof but may be embodied in other forms differing more or less therefrom.

Means are preferably employed to yield- 85 ingly hold the gearing in its two adjustments, said means comprising encircling grooves 13^a in the shaft 13 and a spring-pressed pin 13^b for engaging one or the other of said grooves according to the lon- 90 gitudinal position of the shaft.

What is claimed is:

1. The combination with the ribbon spools and ribbon, of rotary driving mechanism shiftable to alternately turn the spools in 95 opposite directions, ratchet means for operating said driving mechanism, a pair of devices for shifting the driving mechanism in opposite directions each such device being ribbon actuated and also directly op- 100 erated by the ratchet means for operating the driving mechanism.

2. The combination with the ribbon spools and ribbon, of rotary driving mechanism shiftable to alternately turn the spools in 105 opposite directions, ratchet means for operating said driving mechanism shifting means for the driving mechanism having a plurality of distinct movements including an initial movement derived from the 110 traverse of the ribbon and a succeeding movement derived from the ratchet means for operating the driving mechanism.

3. The combination with the ribbon spools and ribbon, of rotary driving mechanism to 115 alternately turn the spools in opposite directions, reciprocating ratchet means for operating said driving mechanism, means for shifting the driving mechanism in opposite directions having a plurality of movements including an initial actuation derived from the traverse of the ribbon and a supplemental actuation by said ratchet means. 120

4. The combination with the ribbon spools and ribbon, of driving mechanism shiftable 125 to alternately turn the spools in opposite directions, means for operating said driving mechanism, and devices set by movement derived from the ribbon and further actuated, in the same direction as in such ribbon- 130

- setting, by said operating means to shift the driving mechanism.
5. The combination with the ribbon spools and ribbon, of driving mechanism shiftable to alternately turn the spools in opposite directions, means for operating said driving mechanism, devices for shifting the latter normally held to inoperative position and movable by the ribbon to a limited extent without affecting the driving mechanism, and means for further actuating said shifting devices in the same direction by the operating means to effect the shift.
10. The combination with the ribbon spools and ribbon, of driving mechanism shiftable to alternately turn the spools in opposite directions, means for operating said driving mechanism, devices for shifting the latter yieldingly held to inoperative position and movable by the ribbon to a limited extent without affecting the driving mechanism, and means for further actuating said shifting devices in the same direction by the operating means to effect the shift.
15. The combination with the ribbon and ribbon spools, of a longitudinally movable shaft geared at opposite ends to said spools respectively for alternate driving connection therewith, operating means for turning the shaft to wind the ribbon on one or the other of the spools, and shifters for said shaft, ribbon actuated but otherwise disconnected from the spools, said shifters alternately actuated by said operating means and moving independently of each other.
20. The combination with the ribbon and ribbon spools, of a longitudinally movable shaft geared at opposite ends to said spools respectively for alternate driving connection therewith, operating means for turning the shaft to wind the ribbon on one or the other of the spools, shifters for said shaft normally held to inoperative position and movable by the ribbon to a limited extent without affecting the shaft, and means for further actuating said shifters in the same direction by the said operating means.
25. The combination with the ribbon and ribbon spools, of a longitudinally movable shaft geared at opposite ends to said spools respectively for alternate driving connection therewith, operating means for turning the shaft to wind the ribbon on one or the other of the spools, shifters for said shaft yieldingly held to inoperative position and movable by the ribbon to a limited extent without affecting the shaft, and means for further actuating said shifters in the same direction by the said operating means.
30. The combination with the ribbon and ribbon spools, of a longitudinally movable shaft geared at opposite ends to said spools respectively for alternate driving connection therewith, operating means for turning the shaft to wind the ribbon on one or the other of the spools, shifters for said shaft normally held to inoperative position and movable by the ribbon to a limited extent without affecting the shaft, and means for further actuating said shifters in the same direction by the said operating means.
35. The combination with the ribbon and ribbon spools, of a longitudinally movable shaft geared at opposite ends to said spools respectively for alternate driving connection therewith, operating means for turning the shaft to wind the ribbon on one or the other of the spools, shifters for said shaft normally held to inoperative position and movable by the ribbon to a limited extent without affecting the shaft, and means for further actuating said shifters in the same direction by the said operating means.
40. The combination with the ribbon and ribbon spools, of a longitudinally movable shaft geared at opposite ends to said spools respectively for alternate driving connection therewith, operating means for turning the shaft to wind the ribbon on one or the other of the spools, shifters for said shaft normally held to inoperative position and movable by the ribbon to a limited extent without affecting the shaft, and means for further actuating said shifters in the same direction by the said operating means.
45. The combination with the ribbon and ribbon spools, of a longitudinally movable shaft geared at opposite ends to said spools respectively for alternate driving connection therewith, operating means for turning the shaft to wind the ribbon on one or the other of the spools, shifters for said shaft normally held to inoperative position and movable by the ribbon to a limited extent without affecting the shaft, and means for further actuating said shifters in the same direction by the said operating means.
50. The combination with the ribbon and ribbon spools, of a longitudinally movable shaft geared at opposite ends to said spools respectively for alternate driving connection therewith, operating means for turning the shaft to wind the ribbon on one or the other of the spools, shifters for said shaft normally held to inoperative position and movable by the ribbon to a limited extent without affecting the shaft, and means for further actuating said shifters in the same direction by the said operating means.
55. The combination with the ribbon and ribbon spools, of a longitudinally movable shaft geared at opposite ends to said spools respectively for alternate driving connection therewith, operating means for turning the shaft to wind the ribbon on one or the other of the spools, shifters for said shaft normally held to inoperative position and movable by the ribbon to a limited extent without affecting the shaft, and means for further actuating said shifters in the same direction by the said operating means.
60. The combination with the ribbon and ribbon spools, of a longitudinally movable shaft geared at opposite ends to said spools respectively for alternate driving connection therewith, shifters for said shaft normally held to inoperative position, means for dis-

placing said shifters by the ribbon, and actuating means then acting to further move the shifters in the same direction and thereby shift the shaft.

11. The combination with the ribbon and ribbon spools, of a longitudinally movable shaft geared at opposite ends to said spools respectively for alternate driving connection therewith, pivoted shifters for engaging said shaft to move it in opposite directions normally held to inoperative position, means carried by the ribbon for moving said shifters from normal position, and actuating means for acting upon either shifter when so displaced by the ribbon means to cause it to move farther in the same direction and thereby shift the shaft.

12. The combination with the ribbon and ribbon spools, of a longitudinally movable shaft geared at opposite ends to said spools respectively for alternate driving connection therewith, shifters for said shaft normally held to inoperative position, means for displacing said shifters by the ribbon, and a vibrating actuator acting upon either of said shifters when so displaced by the ribbon means to cause it to shift the shaft.

13. The combination with the ribbon and ribbon spools, of a longitudinally movable shaft geared at opposite ends to said spools respectively for alternate driving connection therewith, pivoted shifters for engaging said shaft to move it in opposite directions normally held to inoperative position, means carried by the ribbon for moving said shifters from normal position, and a vibrating actuator acting upon either of said shifters when so displaced by the ribbon means to cause it to shift the shaft.

14. The combination with the ribbon spools and the ribbon having catches near its ends, of a longitudinally movable shaft geared at opposite ends to said spools respectively for alternately driving the same, pivoted shifters having arms acted upon by said ribbon-catches and arms to act against shoulders of the shaft and also arms by which to complete shaft-shifting movement, and a vibrating actuator normally disengaged from said last named arms of the shifters but adapted to act upon either of the same when displaced by a ribbon catch, substantially as and for the purpose described.

15. The combination with the ribbon spools and the ribbon having catches near its ends, of a longitudinally movable shaft geared at opposite ends to said spools respectively for alternately driving the same, pivoted shifters having arms acted upon by said ribbon-catches and arms to act against shoulders of the shaft and also weighted arms by which to complete shaft-shifting movements, and a vibrating actuator normally disengaged from said last

- named arms of the shifters but adapted to act upon the same when displaced by a ribbon catch, substantially as and for the purpose described.
- 5 16. The combination with the ribbon spools and the ribbon having catches near its ends, of a longitudinally movable shaft geared at opposite ends to said spools respectively for alternately driving the same, 10 pivoted shifters having arms acted upon by said ribbon-catches and arms to act against shoulders of the shaft and also arms with beveled ends by which to complete shaft-shifting movements, and a vibrating actuator normally disengaged from said last 15 named arms of the shifters but adapted to act upon the beveled end of either when displaced by a ribbon catch, substantially as and for the purpose described.
- 20 17. The combination with the ribbon spools and the ribbon having catches, near its ends, of a longitudinally movable shaft geared at opposite ends to said spools respectively for alternately driving the same, 25 pivoted shifters having arms acted upon by said ribbon-catchers and arms to act against shoulders of the shaft and also arms by which to complete shaft-shifting movements, and a vibrating actuator normally 30 disengaged from said last named arms of the shifters but having beveled portions adapted to act upon the same when displaced by the ribbon catches, substantially as and for the purpose described.
18. The combination with the ribbon 35 spools and the ribbon having catches near its ends, of a longitudinally movable shaft geared at opposite ends to said spools respectively for alternately driving the same, pivoted shifters having arms acted upon by 40 said ribbon-catches and arms to act against shoulders of the shaft and also arms with beveled ends by which to complete shaft-shifting movements, and a vibrating actuator normally disengaged from said last 45 named arms of the shifters, but having beveled projections to coact with the beveled ends of said arms when the shifters are displaced by the ribbon catches, substantially as and for the purpose described. 50
19. The combination with the ribbon spools, the ribbon and a longitudinally movable shaft arranged to be shifted alternately into engagement with the respective ribbon spool mechanisms, a pair of pivoted dogs arranged to engage the longitudinally movable shaft near opposite ends thereof to shift it alternately in opposite directions, means adapted to be operated by the traverse of the ribbon for initiating the movement of each dog in a direction to shift the shaft, a reciprocating means for rotating the shaft adapted to consummate the movement initiated by the ribbon traverse. 55
